(57) **CLAIM**

We claim the ornamental design for a guiding tool for
sewing machine, as shown.

DESCRIPTION

FIG. 1 is a perspective view of a guiding tool for sewing
machine according to our design as seen from the front side
thereof;

FIG. 2 is another perspective view of the same as seen from
the rear side thereof;

FIG. 3 is a front elevational view of the same;

FIG. 4 is a rear elevational view of the same;

FIG. 5 is a top plan view of the same;

FIG. 6 is a bottom view of the same;

FIG. 7 is a left side elevational view of the same; and,

FIG. 8 is a right side elevational view of the same.
